UNITED STATES PATENT OFFICE.

JAMES H. CLARK, OF DETROIT, MICHIGAN, ASSIGNOR TO BRIGGS MANUFACTURING COMPANY, OF DETROIT, MICHIGAN, A CORPORATION OF MICHIGAN.

TOP-BOW-JOINT CONSTRUCTION.

Application filed July 14, 1926. Serial No. 122,383.

This invention relates generally to vehicle body frame constructions and more particularly to the top and side frame constructions of motor buses.

5 It is an object of the present invention to provide a bus construction in which the top thereof can be assembled separately and then secured as a unit to the sides of the bus.

Another object is to provide novel means 10 of joining the pillars to the upper guard rails and roof rails so as to effect a strong, rugged construction that can be quickly assembled.

Another object is to provide a top bow 15 bracket construction having bolt-retaining means so as to provide against an accidental displacement of the bolts, especially when the top is attached as a unit to the top framework.

20 With these and other objects in view, the invention resides in certain novel features of construction, combinations and arrangements of parts as will be more fully described and particularly pointed out in the 25 appended claims.

In the accompanying drawings:

Figure 1 is a side elevation of the frame construction embodying my invention;

Figure 2 is a vertical sectional view of the 30 same;

Figure 3 is a sectional view on line D—D of Figure 2;

Figure 4 is a sectional view on line E—E of Figure 2.

35 In the drawings the numeral 1 designates a side wall of a motor bus, while at 2 is shown a portion of a bus roof secured to the side wall in a manner to be hereinafter described. Extending from top to bottom of 40 the side wall is a channel-shaped pillar 3 having its open portion facing outwardly, said pillar being provided with a corresponding channel-shaped cover 4 embracing the same and closing the channel thereof.

45 As shown in Figure 4, the side portions of the pillar terminate short of the base of the cover and the sides of the cover likewise terminate short of the base of the pillar.

Inner and outer ventilating panels 5 and 50 6 are spaced from each other, forming a longitudinal air passage extending throughout the length of the bus and are connected at their lower edges in any suitable manner to upstanding portions 7 and 8 of an upper guard rail 9, while at their upper edges they

are joined to a roof rail reinforcing member 10 which extends longitudinally of the side of the bus substantially parallel to the upper guard rail 9.

A flanged opening 11 is provided in the 60 horizontal base portion of the upper guard rail, through which the pillar 3 with its cover 4 projects, the cover portion terminating at the upper edge of the flange as at 12 and being butt-welded thereto and to the 65 pillar 3. This forms a very strong and rugged joint between the upper guard rail, pillar and cover and provides for a quick and easy assembly of parts.

As shown, the pillar extends upwardly between the panels 5 and 6 and passes through an opening 13 in the roof rail reinforcing member 10, said opening being directly above and in alignment with the lower opening 11 aforesaid and which is likewise provided with a similarly formed upstanding flange 14 to which the edges of the pillar are butt welded as at 15.

The roof rail reinforcing member 10 is substantially U-shaped in formation and, as 80 shown, the upper edge of the panel 6 is suitably connected to the inner side portion thereof as at 16, while the upper edge of the outer panel 5 is flanged inwardly and connected to the base of the reinforcing member, as at 17.

Provided at the outer side of the reinforcing member 10 is an outwardly extending lateral flange 18, while above the opening 13 is positioned an inverted U-shaped 90 plate 19, the side walls of which lie within the side walls of the roof rail reinforcing member and the base portion of which lies in substantially the same horizontal plane as the lateral flange 18. Transversely arranged 95 within the member 10 are supporting members 20, which are secured preferably by a welding operation to the web of the plate 19 and to the reinforcing member 10, while the side walls of the plate 19 are also preferably 100 welded to the side walls of the reinforcing member 10.

As is readily apparent, any desired number of pillars 3 may be positioned at predetermined points along the side wall of 105 the bus so as to provide sufficient supporting surfaces for the bus roof 2. Extending longitudinally of the bus is a roof rail 21, being adapted to rest upon the flat horizontal support formed by the base portions 110

of the U-shaped plates 19 and the lateral flange 18 of the reinforcing member 10 while extending along the outside of the roof rail and partially supported upon the flange 18 5 is a drip molding 22. Located at intervals along the roof rail and supported thereby are wooden top bows, an end portion of one being represented at 23, and being provided with a metal strengthening strap 24.

10 For attaching the top bow to the roof rail there are provided right and left hand angle brackets 25 having upstanding portions 26 and lateral horizontal portions 27. In order to obtain the proper uniform spacing between the brackets, the portions 27 are mounted upon a base plate 28, which in turn is securely attached to the top of the roof rail in any suitable manner. As shown, suitable bolts 29 clamp the top bow between the brackets 25, while bolts 30 are provided for attaching the roof rail and roof structure 2 to the roof rail reinforcing member 10, the bolts extending through transverse bores in the roof rail and projecting down through suitable openings formed in the plate 19, supports 20 and reinforcing member 10.

In view of the fact that the roof 2 is assembled as a unit, it is necessary to provide some means for preventing the bolts 30 from slipping out of place. Such a contingency would necessitate the removal of a portion of the roof covering, causing great delay and added expense in the assembly 35 thereof. To provide against such a condition, the brackets 25 are provided with bolt-retaining flanges 31, which are bent over upon the heads of the bolts after they are slipped into place, thereby securely retaining 40 them in the desired position.

While it is believed that from the foregoing description the nature and advantage of my invention will be readily apparent, I desire to have it understood that I do not 45 limit myself to what is herein shown and de-

scribed and that such changes may be resorted to when desired as fall within the scope of what is claimed.

What I claim as my invention is:

1. In a vehicle body, the combination with a roof rail, of a reinforcing member supporting said roof rail and having an opening therein, a supporting pillar for said roof rail and reinforcing member projecting through the opening in said reinforcing member, and means for securing said pillar thereto.

2. In a vehicle body, the combination with a roof rail, of a reinforcing member supporting said roof rail and having an opening therein provided with an upstanding flange, and a supporting pillar for said roof rail and reinforcing member projecting through said opening in the reinforcing member and secured to said flange.

3. In a vehicle body, the combination with a roof rail, of a reinforcing member supporting said roof rail and having an opening therein provided with an upstanding flange, and a supporting pillar for said roof rail and reinforcing member projecting through the opening in said reinforcing member, the edges of said pillar being butt welded to said upstanding flange.

4. In a vehicle body, the combination with a pillar, of a U-shaped reinforcing member secured to the top of said pillar and supported thereby, the outer edge of said reinforcing member being provided with a lateral flange, an inverted U-shaped plate secured in said reinforcing member and having its base portion lying substantially in the same horizontal plane as the lateral flange of the reinforcing member and forming therewith a flat base, and a roof rail seating upon said base and secured to said reinforcing member.

In testimony whereof I affix my signature.

JAMES H. CLARK.
